COOKING VESSEL

Eduard Bay, Hohlstrasse, 5412 Ransbach,
Westerwald, Germany

Continuation of design application Ser. No. 17,400, May
8, 1969. This application July 31, 1970, Ser. No. 24,250

Term of patent 14 years

Int. Cl. D7—02

U.S. Cl. D44—1

FIG. 1.

FIG. 2.

FIG. 3.

FIG. 4A.

FIG. 4B.

FIG. 5A.

FIG. 5B.

FIG. 1 is a top plan view of a cooking vessel showing my new design;

FIG. 2 is a side elevational view;

FIG. 3 is an end elevational view;

FIGS. 4a and 4b are developed views on an enlarged scale of the areas within the boxes shown in FIG. 1 and designated 4a and 4b, respectively; and

FIGS. 5a and 5b are developed views on an enlarged scale of areas on the bottom half of the cooking vessel corresponding to the areas within the boxes shown in FIG. 1.

This application is a continuation of my pending application Ser. No. D. 17,400, filed May 28, 1969 and now abandoned.

I claim:

The ornamental design for a cooking vessel, as shown.
